UNITED STATES PATENT OFFICE.

IVOR D. THOMAS, OF PALMYRA, AND PAUL H. DOUGLAS, OF CLEVELAND HEIGHTS, OHIO, ASSIGNORS TO THE WELLMAN-SEAVER-MORGAN COMPANY, OF CLEVELAND, OHIO, A CORPORATION OF OHIO.

AUTOMATIC ROPE TAKE-UP FOR LEVELER BARS.

Application filed February 26, 1926. Serial No. 90,938.

- This invention relates to coke oven levelers and more particularly to the mechanism by which reciprocating movements are imparted to the leveler bar.
- 5 In the operation of a coke plant it is essential that the charge of coal be leveled after it has been introduced into the oven chamber. This is usually accomplished by means of a leveler bar mounted on a carriage which travels along the front of the oven and adapted to be projected into the oven chamber near its top through a small door opening provided in the main oven door. The leveler bar is a long poker-like 10 member built up of structural steel shapes and plates and is projected into and retracted from the oven by a suitable motor which drives a drum upon which is wound two ropes, one paying out while the other 15 winds on the drum. Both ropes are connected to the leveler bar near its outermost end, one rope extending over a sheave on the frame adjacent the oven and serving to move the ram into the oven and the other 20 passing over a sheave adjacent the outermost end of the leveler bar supporting frame and serving to retract the leveler bar. The usual operation of leveling a coal charge 25 consists of running the leveler bar into an oven practically its full length and then reciprocating the bar back and forth for a short portion of its stroke a number of times which action levels the coal. As the reversing motion of the bar is more or less sudden 30 it is essential that no slack be allowed in either rope otherwise a whipping action would occur producing excessive strains on the ropes and thereby materially decreasing their life.
- 35 It is the object of the present invention to provide an effective device for automatically keeping the bar operating, ropes taut and for taking up any stretch of ropes in such manner as to maintain at all times a 40 certain constant pull on the ropes. A tension is preferably maintained upon the ropes by means of a counterweight acting upon one of the guide sheaves which is movably mounted, and one of the objects of the 45 present invention is to provide means in connection with the counterweight for lifting the same to release tension on the ropes in order to permit them to be easily shortened or replaced.
- 50

A further object is to provide means in 55 connection with the take-up device for preventing vibration of the take-up sheave during the operation of the leveler bar.

The leveler bar is preferably mounted in a horizontal guide frame which is adjustable 60 vertically on the leveler bar supporting structure so that the leveler bar can be adjusted to the proper height for the battery of coke ovens with which the leveler is being used, and an important feature of the 65 invention is the mounting of the rope take-up device entirely upon the leveler bar guide frame so that no adjustment of the take-up device is required when the height of the 70 leveler bar is changed.

The following description and accompanying drawings set forth certain means embodying the invention, the disclosed means, however, constituting but one of the various 75 mechanical forms in which the principle of the invention may be employed.

Reference should be had to the accompanying drawings forming a part of this specification in which Fig. 1 is a side elevation showing the leveler bar and its guide 80 frame, the operating cables and the drum for operating the cables, together with a portion of the supporting structure upon which the leveler bar guide frame is mounted; Fig. 2 is a fragmentary top plan view 85 showing the rear end of the leveler bar guide frame and the cable take-up device mounted thereon; Fig. 3 is a side elevation of the rear end of the guide frame showing the cable take-up device; Fig. 4 is a section 90 taken on line 4—4 of Fig. 1.

Referring to the accompanying drawings, the only portions of the leveler bar supporting structure shown are the supporting standards 1 which are arranged in pairs 95 and receive the leveler bar guide frame 2 between them. The leveler bar guide frame 2 is adjustably supported between the standards by means of screws 3 fixed at their lower ends to crossbars 4 of the guide 100 frame and extending up through crossbars 5 connecting upper ends of standards 1. The guide frame may be adjusted up and down by means of hand-wheels 6 which have threaded engagement with the screws 3 and 105 bear upon the tops of the crossbars 5; by turning the hand-wheels 6 the guide frame 2 may be raised or lowered, and for posi-

tively retaining the guide frame in adjusted position retaining nuts 7 may be provided on the screws 3 beneath the crossbars 5 so that they may be screwed into engagement 5 with the bottoms of the bars 5. The guide frame 2 is provided at intervals with flanged supporting rollers 8 and flanged guide rollers 9 above the rollers 8, the lever bar 10 being mounted to slide between the lower 10 supporting rollers 8 and upper guide rollers 9.

The leveler bar 10 is moved back and forth by means of operating cables 12 and 13, both of which are anchored at one end 15 to the leveler bar 10 adjacent the rear end thereof by means of a suitable anchoring clamp 14. The operating cable 12 extends over a guide sheave 15 journaled in a housing 16 attached to the forward end of the 20 guide frame 2 and the operating cable 13 extends over a take-up sheave 17 journaled on a shaft 18 which is suspended by a pair of links 19 from the guide frame 2 adjacent the rear end thereof. Between the sheaves 25 15 and 17 grooved sag carriers 20 are provided for the operating cables immediately adjacent the underside of the leveler bar, the sag carriers 20 being mounted between the flanged supporting rollers 8 upon which 30 the leveler bar rests. Both of the operating cables 12 and 13 extend to a winding drum 21 below the leveler guide frame, the cables being attached to the winding drum so 35 that one cable winds up on the drum while the other is unwound therefrom. The winding drum 21 is operated by an electric motor or other suitable driving mechanism (not shown) to advance the leveler bar into an oven, to retract the bar from the oven and 40 to impart the reciprocating motions to the bar while in the oven for levelling the charge of coal.

Means is provided for exerting a constant outward pull upon the movably mounted 45 sheave 17 sufficient to take up the slack in the cables 12 and 13 and to maintain these cables at all times under tension. The outward pull on the sheave 17 is exerted by a counterweight lever pivotally mounted upon 50 a cross shaft 22 extending across the guide frame beneath the leveler bar outwardly of the sheave 17. This counterweight lever consists of a segment shaped counterweight 23 which has an integral laterally projecting sleeve 24 through which the shaft 22 extends, the sleeve 23 having a pair of spaced arms 55 integral therewith between which is pivoted the outer end of a link 26 which straddles the take-up sheave 17 and is connected to the shaft 18 of the sheave upon opposite sides of the sheave. The weight of the arm 23 of the lever tends to swing the same 60 downwardly from the position shown in Figs. 1 and 3 and, through the arm 25 and link 26, exerts an outward pull on the

sheave 17. The segment shaft counterweight arm 23 has ratchet teeth 23^a formed on the periphery thereof and a holding pawl 27 is provided which is engageable with the ratchet teeth 23^a to prevent upward 70 movement of the arm 23; the holding pawl 27 is pivoted upon a shaft 28 carried by the guide frame 2 and has a laterally projecting pin 29 by which it may be operated as will be presently explained. The pawl 27 is also formed integrally with a second holding pawl 30 which is so positioned with respect to the pawl 27 that it is held out of engagement with the ratchet teeth 23^a while the pawl 27 is in engaging position. One 80 or the other of the pawls 27 or 30 may be yieldingly held in engagement with the ratchet teeth 23^a by means of a weighted arm 31 which is pivoted upon the shaft 28 and is provided on opposite sides thereof with engaging shoulders 31^a and 31^b. When the weighted arm is at one side of the pivot shaft 28 it is held by gravity with its shoulder 31^a in engagement with the pin 29 and yieldingly holds the pawl 27 in engagement with the ratchet. When the arm 31 is swung to the opposite side of the pivot 85 shaft 28 the shoulder 31^b engages with pin 29 and holds the pawl 27 out of engagement with the ratchet and the pawl 30 yieldingly in engagement therewith. The pawl 27 prevents upward movement of the arm 23 and the pawl 30 is designed to prevent downward movement of the arm 23. The pawl 27 is kept in engagement with the ratchet while the leveler bar is being operated and serves to prevent any upward movement of the counterweight arm which cause slackening of the cables. Sudden jerks on the operating cables in the operation of the leveler bar tend to pull the take-up sheave inwardly and raise the counterweight and were it not for pawl 27 would set up a vibratory movement of the take-up sheave and counterweight and a whipping action on 100 the cables. The pawl 30 serves to hold the counterweight arm 23 in a position to which it may be lifted and is used whenever it is desired to slack the cables in order to shorten them or to replace them.

The counterweight arm 23 must be heavy enough to keep the cable 13 taut at all times during the operation of the leveler. Since the weight of the lever 23 is too great to permit of its being conveniently lifted by hand, means is provided on the guide frame for jacking up the weight. This means consists of a lever 32 adapted to receive an operating handle and pivoted at 33 to the frame adjacent the periphery of the ratchet 26, the lever 32 being provided with a pivoted pawl 34 which is adapted to be swung into a position in which it engages with the ratchet as shown in dotted lines in Fig. 3. Whenever it is desired to slacken the cables the 110 120 125 130

- weight 31 is swung rearwardly to bring the shoulder 31^a into engagement with pin 29 on the pawl 27, shifting the pawl 27 out of engagement with the ratchet and the pawl 30 into engagement therewith. The pawl 34 is then swung into ratchet engaging position and the lever 32 operated to shift the ratchet upwardly, one tooth at a time, the pawl 30 holding the ratchet after each actuation in the position into which it has been shifted by the lever and, after the cables are sufficiently slack, retaining the counterweight while the desired operations are being performed on the cables. When the leveler bar 15 is to be operated the weighted arm 31 will be positioned with the shoulder 31^a in engagement with the pin 29 to yieldingly hold the pawl 27 in engagement with ratchet 23^a so that the weight of the arm 23 acts to hold 20 the cables taut and the weighted arm is held against upward movement from any position to which it moves by gravity, so that vibratory motions can not be imparted to the take-up sheave in the operation of the device.
- 25 Having described our invention, we claim:
1. In a device of the character described, a reciprocating member, a supporting frame having a guideway for said member, sheaves adjacent opposite ends of said guideway, a winding drum, operating cables, each attached at one end to said member, extending over one of the sheaves and attached at the opposite end to said drum, a movable support for one of said sheaves, means for taking up slack in the cables comprising a counterweighted lever pivoted to the frame and connected to said movable sheave support, and means engageable with said lever to hold the same in adjusted positions.
  - 40 2. In a device of the character described, a reciprocating member, a supporting frame having a guideway for said member, sheaves adjacent opposite ends of said guideway, a winding drum, operating cables, each attached at one end to said member, extending over one of the sheaves and attached at the opposite end to said drum, a movable support for one of said sheaves, a ratchet connected to said lever and a pawl acting on said 45 ratchet to prevent movement of the lever in a direction to loosen the cables.
  - 50 3. In a coke oven leveler, a supporting structure, a horizontal guide frame mounted for vertical adjustment on said structure, a reciprocable leveler bar mounted in said frame, guide sheaves mounted on said guide frame adjacent opposite ends thereof, a winding drum mounted on said supporting structure independently of said guide frame, operating cables each attached at one end to said drum passing over one of said sheaves and attached at its opposite end to the leveler bar adjacent the rear end thereof, means for 55 movably supporting one of the sheaves, and means for keeping the cables taut comprising a counterpoise mounted on the adjustable frame and connected to the movable sheave support.
  - 60 4. In a coke oven leveler, a supporting structure, a horizontal guide frame mounted for vertical adjustment on said structure, a reciprocable leveler bar mounted in said frame, guide sheaves mounted on said frame adjacent opposite ends thereof, one of said sheaves being movable longitudinally of the frame, operating cables passing over said sheaves and each attached at one end to the leveler bar adjacent the rear end thereof, means on the structure for operating said cables to reciprocate the leveler, means for 65 maintaining the cables taut comprising a counterweighted lever pivoted on the guide frame and connected to the movable sheave, and means for lifting said lever and for retaining the same in adjusted positions.
  - 70 5. In a coke oven leveler, a supporting structure, a horizontal guide frame mounted for vertical adjustment on said structure, a reciprocable leveler bar mounted in said frame, guide sheaves mounted on said frame adjacent opposite ends thereof, one of said sheaves being movable longitudinally of the frame, operating cables passing over said sheaves and each attached at one end to the leveler bar adjacent the rear end thereof, means on the structure for operating said cables to reciprocate the leveler, means for 75 maintaining the cables taut comprising a counterweighted lever pivoted on the guide frame and connected to the movable sheave, and means for lifting said lever and for retaining the same in adjusted positions.
  - 80 6. In a coke oven leveler, a supporting structure, a horizontal guide frame mounted for vertical adjustment on said structure, a reciprocable leveler bar mounted in said frame, guide sheaves mounted on said frame adjacent opposite ends thereof, one of said sheaves being movable longitudinally of the frame, operating cables passing over said sheaves and each attached at one end to the leveler bar adjacent the rear end thereof, means on the structure for operating said cables to reciprocate the leveler, means for 85 maintaining the cables taut comprising a counterweighted lever pivoted on the guide frame and connected to the movable sheave, and means for lifting said lever and for retaining the same in adjusted positions.
  - 85 7. In a coke oven leveler, a supporting structure, a horizontal guide frame mounted for vertical adjustment on said structure, a reciprocable leveler bar mounted in said frame, guide sheaves mounted on said frame adjacent opposite ends thereof, one of said sheaves being movable longitudinally of the frame, operating cables passing over said sheaves and each attached at one end to the leveler bar adjacent the rear end thereof, means on the structure for operating said cables to reciprocate the leveler, means for 90 maintaining the cables taut comprising a counterweighted lever pivoted on the guide frame and connected to the movable sheave, and means for lifting the lever counterweight to slack the cables.
  - 95 8. In a coke oven leveler, a supporting structure, a horizontal guide frame mounted for vertical adjustment on said structure, a reciprocable leveler bar mounted in said frame, guide sheaves mounted on said frame adjacent opposite ends thereof, one of said sheaves being movable longitudinally of the frame, operating cables passing over said sheaves and each attached at one end to the leveler bar adjacent the rear end thereof, means on the structure for operating said cables to reciprocate the leveler, means for 100 maintaining the cables taut comprising a counterweighted lever pivoted on the guide frame and connected to the movable sheave, and means for lifting the lever counterweight to slack the cables.
  - 105 9. In a coke oven leveler, a supporting structure, a horizontal guide frame mounted for vertical adjustment on said structure, a reciprocable leveler bar mounted in said frame, guide sheaves mounted on said frame adjacent opposite ends thereof, one of said sheaves being movable longitudinally of the frame, operating cables passing over said sheaves and each attached at one end to the leveler bar adjacent the rear end thereof, means on the structure for operating said cables to reciprocate the leveler, means for 110 maintaining the cables taut comprising a counterweighted lever pivoted on the guide frame and connected to the movable sheave, and means for lifting the lever counterweight to slack the cables.
  - 110 10. In a coke oven leveler, a supporting structure, a horizontal guide frame mounted for vertical adjustment on said structure, a reciprocable leveler bar mounted in said frame, guide sheaves mounted on said frame adjacent opposite ends thereof, one of said sheaves being movable longitudinally of the frame, operating cables passing over said sheaves and each attached at one end to the leveler bar adjacent the rear end thereof, means on the structure for operating said cables to reciprocate the leveler, means for 115 maintaining the cables taut comprising a counterweighted lever pivoted on the guide frame and connected to the movable sheave, and means for lifting the lever counterweight to slack the cables.
  - 115 11. In a coke oven leveler, a supporting structure, a horizontal guide frame mounted for vertical adjustment on said structure, a reciprocable leveler bar mounted in said frame, guide sheaves mounted on said frame adjacent opposite ends thereof, one of said sheaves being movable longitudinally of the frame, operating cables passing over said sheaves and each attached at one end to the leveler bar adjacent the rear end thereof, means on the structure for operating said cables to reciprocate the leveler, means for 120 maintaining the cables taut comprising a counterweighted lever pivoted on the guide frame and connected to the movable sheave, and means for lifting the lever counterweight to slack the cables.
  - 120 12. In a coke oven leveler, a supporting structure, a horizontal guide frame mounted for vertical adjustment on said structure, a reciprocable leveler bar mounted in said frame, guide sheaves mounted on said frame adjacent opposite ends thereof, one of said sheaves being movable longitudinally of the frame, operating cables passing over said sheaves and each attached at one end to the leveler bar adjacent the rear end thereof, means on the structure for operating said cables to reciprocate the leveler, means for 125 maintaining the cables taut comprising a counterweighted lever pivoted on the guide frame and connected to the movable sheave, and means for lifting the lever counterweight to slack the cables.
  - 125 13. In a coke oven leveler, a supporting structure, a horizontal guide frame mounted for vertical adjustment on said structure, a reciprocable leveler bar mounted in said frame, guide sheaves mounted on said frame adjacent opposite ends thereof, one of said sheaves being movable longitudinally of the frame, operating cables passing over said sheaves and each attached at one end to the leveler bar adjacent the rear end thereof, means on the structure for operating said cables to reciprocate the leveler, means for 130 maintaining the cables taut comprising a counterweighted lever pivoted on the guide frame and connected to the movable sheave, and means for lifting the lever counterweight to slack the cables.

- adjacent opposite ends thereof, one of said sheaves being movable longitudinally of the frame, operating cables passing over said sheaves and each attached at one end to the leveler bar adjacent the rear end thereof, means on the structure for operating said cables to reciprocate the leveler, means for maintaining the cables taut comprising a counterweighted lever pivoted on the guide frame and connected to the movable sheave, a ratchet connected to the lever, a pawl engageable with the ratchet to hold the lever against movement in one direction, a pawl engageable with the ratchet to hold the lever against movement in the opposite directions, means for yieldably holding either pawl in engagement with the ratchet and the other pawl out of engagement, and a lever pivoted on the frame and having a pawl engageable with the ratchet to turn the same in a direction to lift the lever counterweight.
8. In a device of the character described, a cable tightener comprising a frame, a sheave movably mounted on the frame, a lever having an arm connected to said sheave, and a segment shaped counterweight arm provided with ratchet teeth, a pawl engageable with said ratchet teeth to prevent upward movement of the counterweight arm, and means for yieldably pressing said pawl against the ratchet.
9. In a device of the character described,

a cable tightener comprising a frame, a sheave movably mounted on the frame, a lever having an arm connected to said sheave, and a segment shaped counterweight arm provided with ratchet teeth, a pawl engageable with said ratchet teeth to prevent upward movement of the counterweight arm, and means for holding said pawl out of engagement with the ratchet, and means carried by the frame for swinging said counterweight arm upwardly.

10. In a device of the character described, a cable tightener comprising a frame, a sheave movably mounted on the frame, a lever having an arm connected to said sheave, and a segment shaped counterweight arm provided with ratchet teeth, a pawl engageable with said ratchet teeth to prevent upward movement of the counterweight arm, a second pawl engageable with the ratchet teeth to prevent downward movement of the counterweight arm, means for holding either one of the pawls in yielding engagement with the ratchet and the other out of engagement therewith, and a lever carried by said frame and having a pawl engageable with the ratchet teeth to move the counterweight arm upwardly.

In testimony whereof, we hereunto affix our signatures.

IVOR D. THOMAS.
PAUL H. DOUGLAS.
